CLAIM

The ornamental design for combination extendible divot tool and golf ball retriever, as shown and described.

DESCRIPTION

FIG. 1 is a perspective view of a combination extendible divot tool and golf ball retriever showing my new design, shown in an extended position;

FIG. 2 is a view similar to FIG. 1, showing the combination extendible divot tool and golf ball retriever in a retracted position;

FIG. 3 is a front elevational view of the combination extendible divot tool and golf ball retriever of FIG. 2;

FIG. 4 is a left side view of the combination extendible divot tool and golf ball retriever of FIG. 2, the right side view being a mirror image thereof;

FIG. 5 is a rear elevational view of the combination extendible divot tool and golf ball retriever of FIG. 2;

FIG. 6 is a bottom plan view of the combination extendible divot tool and golf ball retriever of FIG. 2;

FIG. 7 is a top plan view of the combination extendible divot tool and golf ball retriever of FIG. 2;

FIG. 8 is a perspective view of the combination extendible divot tool and golf ball retriever of FIG. 1, showing the divot tool in use; and,

FIG. 9 is a perspective view of the combination extendible divot tool and golf ball retriever of FIG. 1, showing the golf ball retriever in use.

The matter shown in phantom lines in FIGS. 1–6 and 8–9 is for illustrative purposes only and forms no part of the claimed design.
